(57) **CLAIM**

The ornamental design for a poker game playing surface and environment, shown and described.

DESCRIPTION

This application is related to U.S. Utility application Ser. No. 14/486,390, entitled "Method and System for a Card Game Variant of a Community Style Poker Game." Applicant prays that letters patent be granted for the design of said poker playing surface or environment as set forth herein. FIG. 1 is a plan view of one embodiment of a poker game playing surface and environment;

FIG. 2 is an enlarged plan view of reference No. 2 as shown in FIG. 1;

FIG. 3 is a plan view of a second embodiment of a poker game playing surface and environment; and

FIG. 4 is an enlarged plan view of reference No. 4 as shown in FIG. 3.

FIG. 5 is a plan view of a third embodiment of a poker game playing surface and environment; and

FIG. 6 is an enlarged plan view of reference No. 6 as shown in FIG. 5.

FIG. 7 is a plan view of a fourth embodiment of a poker game playing surface and environment; and,

FIG. 8 is an enlarged plan view of reference No. 8 as shown in FIG. 7.

The small broken lines shown in the drawings represent portions that form no part of the claimed design shown in an embodiment. The large broken lines shown in the drawings represent portions that are enlarged in subsequent figures.

1 Claim, 8 Drawing Sheets
